UNITED STATES PATENT OFFICE.

EZRA N. GIFFORD, OF CLEVELAND, OHIO.

CAR-COUPING.

SPECIFICATION forming part of Letters Patent No. 269,043, dated December 12, 1882.

Application filed November 7, 1882. (No model.)

To all whom it may concern:

Be it known that I, EZRA N. GIFFORD, of Cleveland, in the county of Cuyahoga and State of Ohio, have invented certain new and useful 5 Improvements in Car-Couplers; and I do hereby declare the following to be a full, clear, and exact description of the invention, such as will enable others skilled in the art to which it pertains to make and use the same.

10 My invention relates to improvements in car-couplings; and it consists in parts and combinations of parts, as will be more fully herein-after described and claimed.

The object of my invention is to improve and 15 perfect certain devices for a car-coupling on which I have already obtained Letters Patent—to wit, filed September 15, 1882, and allowed October 13, 1882.

In the drawings, Figure 1 is a transverse 20 vertical sectional view of a draw-head, and showing the coupling-pin, and at C one of my new devices. Fig. 2 is a longitudinal vertical sectional view, showing the coupling-pin in connection, as at d, with my other new device. 25 Fig. 3 is the same view as Fig. 2, and shows at C and d each of the devices of my new invention. Fig. 4 is the same view as Fig. 1, and shows at c one device of my former invention aforesaid. Fig. 5 gives the same view as 30 a portion of Fig. 2, and shows at D one device of my former aforesaid invention.

In Fig. 1, A represents a coupling-pin; a, a pin secured to said coupling-pin and projecting from one side of said coupling-pin.

35 B is the chamber or recess of the draw-head in which said coupling-pin operates.

C is a key or plate fastened in any suitable manner, but preferably by a dovetail, (see Fig. 3,) to the top and side of the draw-head, and 40 projecting over the chamber B in such a manner as to engage the pin a when the draw-pin A is drawn up for the purpose of uncoupling cars and acts as a stop to the pin a, and prevents the draw-pin A from being detached 45 from the draw-head and lost or stolen.

In the device (Fig. 4) as allowed by said Letters Patent a set-screw, c, passed through the side of the draw-head and projected into the chamber B, and was used for the same purpose 50 for which I now devise the plate C—to wit,

for a stop, as aforesaid. I have invented the plate C and desire to substitute it in place of my former device for the following reasons, to wit: first, the said plate C being placed at the extreme top of the draw-head, the draw-pin A 55 can be raised higher in the said chamber B, and therefore will be less liable to come in contact with the coupling-link during the passage of said link into and out of the chamber B in coupling and uncoupling cars; second, the said 60 plate furnishes a larger and better surface for contact with the pin a than a bolt or set-screw, and therefore operates better, and is more durable; third, the plate C is cheaper to make and attach than the former devices, and also requires less adjustment, and is less liable to get 65 loose and be lost.

As shown in Fig. 2, the draw-pin A is provided with a recessed cap, a', extending back far enough to engage with the teat D when 70 the coupling-pin is raised and tilted back, thus making a firm support for said pin in said raised position, as allowed by said Letters Patent. The end of the teat D, as used in our former device aforesaid, is more clearly shown 75 in Fig. 5. I now devise a depression, d, in the top of said teat D, in which the wall or edge of said recessed cap a' may be placed, forming a temporary support for said draw-pin A 80 while cars are being coupled or uncoupled. The engagement of said cap a' with said depression d is so slight that the concussion of 85 the cars will break the said engagement and cause the coupling-pin A to fall by its own gravity into its place in the chamber B and engage the coupling-link, and thus fasten or couple the cars without further manipulation.

In our former device, as allowed in said Letters Patent, a branch chamber was provided wherein the point of said draw-pin rested for 90 temporary support in coupling and uncoupling cars, as aforesaid; but the accumulation of snow and ice in said branch chamber sometimes renders this device inoperative. Hence I have invented the said device—to wit, the 95 impression d on the end of the teat D—and desire to substitute it in place of my former device of a branch chamber, as aforesaid.

What I claim is—

1. In a car-coupling device, the combination, 100

with the coupling-pin A and the pin a , of the plate C, substantially as and for the purpose shown and described.

2. In a car-coupling device, the combination, with the teat D, the coupling-pin A, and the recessed cap a' , of a depression, d , in the end of the teat D, substantially as and for the purpose set forth.

In testimony whereof I sign this specification, in the presence of two witnesses, this 24th day of October, 1882.

EZRA N. GIFFORD.
